US0D1028026S

(12) **United States Design Patent** (10) Patent No.: **US D1,028,026 S**
(45) Date of Patent: ** May 21, 2024

(54) **SPUNLACE MACHINE**

(71) Applicant: **Jiangsu Yingyang Nonwoven Machinery Co., Ltd.**, Changshu (CN)

(72) Inventor: **Liyuan Fan**, Changshu (CN)

(73) Assignee: **JIANGSU YINGYANG NONWOVEN MACHINERY CO., LTD.**, Changshu (CN)

(**) Term: **15 Years**

(21) Appl. No.: **29/816,154**

(22) Filed: **Nov. 19, 2021**

(30) **Foreign Application Priority Data**

May 31, 2021 (CN) 202130328319.8

CLAIM

The ornamental design for a spunlace machine, as shown and described.

DESCRIPTION

FIG. 1 is a top perspective view of a spunlace machine showing my new design;

FIG. 2 is a front view thereof;

FIG. 3 is a rear view thereof;

FIG. 4 is a bottom side view thereof;

FIG. 5 is a top view thereof;

FIG. 6 is a left side view thereof;

FIG. 7 is a right side view thereof; and,

FIG. 8 is a bottom perspective view thereof.

(Continued)

The broken lines depict portions of the spunlace machine
that form no part of the claimed design.

1 Claim, 8 Drawing Sheets
